[57] CLAIM

The ornamental design for a packaging structure for a textile article, as shown and described.

DESCRIPTION

FIG. 1 is a front perspective view of a packaging structure for a textile article according to our new design;

FIG. 2 is a right side elevational view;

FIG. 3 is a front elevational view thereof;

FIG. 4 is a left side elevational view thereof;

FIG. 5 is a rear elevational view thereof;

FIG. 6 is a top plan view thereof; and,

FIG. 7 is a bottom plan view thereof.

The broken line showing of the boundaries of the claimed design on the front surface, form no part thereof. The broken line showing of environmental structure in FIGS. 1, 2 & 4 are for illustrative purposes only and form no part of the claimed design.

1 Claim, 4 Drawing Sheets
